ELMER E. WILKINSON AND SAUL ARONSON, OF NEW YORK, N. Y.; SAID ARONSON
ASSIGNOR TO SAID WILKINSON.

WINDING AND SETTING MECHANISM FOR CLOCKS.

1,070,216.

Specification of Letters Patent.

Patented Aug. 12, 1913.

Application filed June 5, 1912. Serial No. 701,748.

To all whom it may concern:

Be it known that we, ELMER E. WILKINSON and SAUL ARONSON, citizens of the United States of America, and residents of the 5 borough of Brooklyn, county of Kings, city and State of New York, and borough of Manhattan, city, county, and State of New York, respectively, have invented certain new and useful Improvements in 10 Winding and Setting Mechanism for Clocks, of which the following is a specification.

Our invention relates to winding and setting mechanism of clocks and like time pieces, and comprises mechanism whereby 15 the clock may be wound, and the hands set, by rotating back and forth the clock movement.

The improved clock herein described is particularly adapted for mounting on the 20 dash-board of an automobile or other vehicle, or for mounting on a bulk-head or partition of a boat. It is, however, convenient for use in various other locations.

The object of our invention is to provide 25 simple and easily operated means for winding and setting clocks, and which shall not comprise any separate winding or setting member, such as a key, nor shall it comprise a projecting stem or the like.

30 We will now proceed to describe our invention with reference to the accompanying drawings, and will then point out the novel features in claims.

In the drawings: Figure 1 shows a front 35 elevation of the clock, and Fig. 2 a central longitudinal section of the cases of the clock, the mechanism being shown in the main in elevation. Fig. 3 shows a transverse section on the line $x-x$ of Fig. 2, 40 looking toward the rear. Fig. 4 shows a rear elevation of the movement case. Fig. 5 shows a transverse section of the line $x-x$ of Fig. 2, looking toward the front. Fig. 6 is a view similar to Fig. 2, except that the 45 movement case is shown drawn out into hand-setting position.

In the drawings 1 designates the base 50 plate of the clock and 2 the outer case secured to and substantially forming a part of the base.

3 designates the inner or movement-case, within which is mounted the dial 4, the movement plates 5, 6 and 7, and the main-spring barrel 8.

We have not in the drawings indicated 55 all of the gearing for transmitting motion from the main-spring to the hands of the clock, as such gearing forms no portion of our present invention.

The inner or movement-case 3 has a back 60 or base 9 provided with an annular flange 10, the purpose of which will be explained hereafter. This movement case is arranged to be rotated back and forth within the outer case 2, its motion being limited by a 65 pin 11 secured to a centrally bossed plate 12, itself secured to base 1, this pin 11 projecting through a slot 13, in the back 9 of the movement-case 3. A helical spring 14 is connected at one end to this pin 11, and at 70 its other end is provided with an out-turned projection 15 engaging one side of an opening 16 in back plate 9, the arrangement being such that when the movement-case 3 is rotated clockwise, such rotation is opposed by a spring 14, and as soon as the movement-case is released, said spring 14 will move the movement-case back to first position.

17 designates the main spring-winding 80 arbor. This arbor has a bearing in plate 12, above mentioned, and in the rear movement plate 7, and has secured to it a ratchet wheel 18, the ratchet 19 of which is pivoted to the plate 12 at 20. Said ratchet is provided 85 with the usual ratchet spring 21, and with a tooth 22, to engage the teeth of the ratchet wheel 18. The arbor 17 is further provided with a gear wheel 23 which, when the parts are in normal position, is in mesh 90 with the gear 24 on the arbor 25 of the main-spring, the latter being, as usual, within the barrel 8.

The movement case 3 is provided with a screw-connected ring 3^a, by which said movement case may be rotated for winding the clock or for setting the hands. This ring 3^a carries the usual glass 3^b which protects the hands and dial of the clock. During clockwise rotation of the movement case one of 100 the teeth of ratchet wheel 18 is engaged by the tooth 22 of ratchet 19 and the ratchet wheel is held stationary; but during the backward rotation of the movement case the ratchet wheel slips idly under the ratchet; 105 the result being that motion is transmitted to gear 24 and the spring is wound. For setting the clock the entire movement case 3

with the movement within it, is arranged to be drawn forward so as to bring a pinion 26 on a shaft 27 into mesh with a gear 28 on the main spring winding arbor 17. To so 5 pull the movement case 3 forward, the ring 3^a, screw connected to the case 3, as shown particularly in Figs. 2 and 6, is grasped and drawn forward. Fig. 6 shows the movement case in the resulting setting position. 10 While this movement of the movement case 15 draws the gear 26 into mesh with the gear 28, the same movement draws the winding gear 24 out of mesh with the winding gear 23. The result is therefore to throw the winding gear out of action and throw the setting mechanism into action; for shaft 27, upon which pinion 26 is mounted, connects with the usual hand-driving train 29 located between the front movement plate 5 and the dial 4.

When the movement case 3 is drawn into the forward or setting position shown in Fig. 6, the flange 10 on the back 9 of the movement case 3 embraces the ratchet 19 of the winding mechanism so closely that the tooth 22 of that ratchet cannot move out of engagement with the teeth of the ratchet wheel 18. Said flange, by so holding the ratchet in engagement with the ratchet wheel, in effect locks the gear wheel 28 stationary, against movement in either direction, so that rotation of the movement case when in the position shown in Fig. 6, effects rotation of the pinion 26, shaft 27 and the operation of the hand-driving train 29. 25 Normally the movement case is held in the position shown in Fig. 2 by a spring 30 shown particularly in Figs. 2 and 5; the arms of which spring tend to press the back 30 of the movement case 3 backward. During the operation of setting the hands, the movement case 3 is held forward in the position shown in Fig. 6, against the tension of this spring; and as soon as the movement case is 40 released, the spring 30 throws it back into the position shown in Fig. 2.

The operation of the winding and setting mechanism is therefore as follows: To wind the clock the ring 3^a is rotated forward and back through an angle represented by the slot 13, or through any convenient smaller angle; and during each forward or clockwise rotation of the ring 3^a (and therefore of the movement case 3 and the movement 50 within it) the ratchet 19 engages the teeth of ratchet wheel 18, and holds said ratchet wheel stationary, so causing gear 23 to impart motion to gear 24 and to wind the main spring, while during the backward rotation 55 said ratchet 19 slips over the ratchet wheel 18 stationary. To set the hands, the movement case 3 is drawn forward by means of the ring 3^a, thus disconnecting gears 23 and 24 of the spring winding train and inter- 60 65 meshing gears 26 and 28 of the hand setting

mechanism, and then, by rotating ring 3^a in either direction, as circumstances may require, the hands are set, after which the ring 3^a is released, and the spring 30 draws the movement case back to the position shown 70 in Fig. 2.

What we claim is:—

1. A clock comprising in combination a base, a movement case rotatable with respect to said base and adapted to receive and carry the movement of said clock, a winding train for a movement so carried comprising gears carried by said case for winding a main spring of such movement, and a ratchet and ratchet wheel, one of which is mounted on the driving member of the winding train, and the other on a portion of the clock which is stationary with relation to the base, and means enforcing alternate forward and backward rotation of the 80 movement case for winding the clock.

2. A clock comprising in combination a base, a movement case rotatable with respect to said base and adapted to receive and carry the movement of said clock, a winding train for a movement so carried comprising gears carried by said case for winding a main spring of such movement, and a ratchet and ratchet wheel, one of which is mounted on the driving member of the winding train, and the other on a portion of the clock which is stationary with relation to the base, and a spring tending to return the movement case when the latter is rotated.

3. A clock comprising in combination a base, a movement case rotatable with respect to said base and adapted to receive and carry the movement of said clock, a winding train for a movement so carried comprising gears carried by said case for winding a main spring of such movement, and a ratchet and ratchet wheel, one of which is mounted on the driving member of the winding train, and the other on a portion of the clock which is stationary with relation to the base, a spring tending to return the movement case when the latter is rotated, and means enforcing alternate forward and backward rotation of the movement case for winding the clock.

4. A clock comprising in combination a base, a movement case rotatable with respect to said base and adapted to receive and carry the movement for said clock, said movement case having in it a curved slot, a winding train for a movement so carried comprising gears carried by said case for winding a main spring of such movement, and a ratchet and ratchet wheel, one of which is mounted on the driving member of the winding train, and the other on a portion of the clock which is stationary with relation to the base, and a pin secured to said base and projecting through said slot 130

and serving, with the slot, to enforce alternate forward and backward rotation of the movement case for winding the clock.

5. A clock comprising in combination a base, a movement case rotatable with respect to said base and adapted to receive and carry the movement for said clock, said movement case having in it a curved slot, a winding train for a movement so carried comprising gears carried by said case for winding a main spring of such movement, and a ratchet and ratchet wheel, one of which is mounted on the driving member of the winding train, and the other on a portion of the clock which is stationary with relation to the base, a pin secured to said base and projecting through said slot and serving, with the slot, to enforce alternate forward and backward rotation of the movement case for winding the clock, and a spring, one end of which is connected to said pin and the other end of which is connected to said movement case, said spring tending to return the movement case when the latter is rotated.

6. A clock comprising a base, a movement case rotatable with respect to said base and adapted to receive and carry the movement of said clock, a winding train for a movement so carried comprising gears carried by said case, and a gear and an arbor therefor carried by said base, a ratchet wheel and a ratchet therefor, one of which is mounted upon said arbor and the other upon a portion of the clock which is stationary with respect to said base, said movement case adapted to be moved axially with respect to said base, thereby disconnecting two of the gears of the winding train, a hand-driving train, and a gear drivingly connected to such hand-driving train and arranged to be moved axially with the movement case, said arbor provided with a gear with which the said gear of the hand-driving train intermeshes when the case is moved axially from the winding to the setting position.

7. A clock comprising a base, a movement case rotatable with respect to said base, a winding train comprising gears carried by said case, and a gear and an arbor therefor carried by said base, a ratchet wheel and a ratchet therefor, one of which is mounted upon said arbor and the other upon a portion of the clock which is stationary with respect to said base, said movement case adapted to be moved axially with respect to said base, thereby disconnecting two of the gears of the winding train, a hand-driving train, and a gear drivingly connected to such hand-driving train and arranged to be moved axially with the movement case, said arbor provided with a gear with which the said gear of the hand-driving train intermeshes when the case is moved axially from

the winding to the setting position, and means for locking the said ratchet and ratchet wheel against relative movement when the case is so moved axially to setting position.

8. A clock comprising a base, a movement case rotatable with respect to said base and adapted to receive and carry the movement of said clock, a winding train for a movement so carried comprising gears carried by said case, and a gear and an arbor therefor carried by said case, a ratchet wheel and a ratchet therefor, one of which is mounted upon said arbor and the other upon a portion of the clock which is stationary with respect to said base, said movement case adapted to be moved axially with respect to said base, thereby disconnecting two of the gears of the winding train, a hand-driving train, and a gear drivingly connected to such hand-driving train and arranged to be moved axially with the movement case, said arbor provided with a gear with which the said gear of the hand-driving train intermeshes when the case is moved axially from the winding to the setting position, and a spring tending to return the movement case from setting to winding position.

9. A clock comprising in combination a base, a movement case mounted to rotate with respect thereto and also to be moved axially with respect thereto from winding to setting position, a spring winding train comprising gears and an arbor, the latter coaxial with the case, a ratchet wheel on said arbor and in driving connection with the winding train, a ratchet for said ratchet wheel, pivoted to the base, said winding train arranged to be thrown out of operation when the movement case is moved axially from winding to setting position, and a hand-driving train comprising a gear arranged to be moved axially with the movement case, said arbor provided with a gear with which the said gear of the hand-driving train engages when the movement case is moved to setting position, said movement case provided with a flange which embraces the ratchet when the movement case is in setting position, and holds said ratchet against disengagement from its ratchet wheel, said flange being out of position to engage said ratchet when the movement case is in winding position.

10. A clock comprising in combination a base, a movement case rotatable about its central axis with respect to said base and adapted to receive and carry the movement of said clock, a winding train for a movement so carried operated by rotation of the movement case, and automatic means for returning said case to normal position.

11. A clock comprising in combination a base, a movement case rotatable about its central axis with respect to said base and adapt-

ed to receive and carry the movement of
said clock, a winding train and a hand set-
ting train for the movement so carried oper-
able, the one or the other at will, by rotation
5 of the movement case, and automatic means
for returning said case to normal position.

In testimony whereof we have signed this

specification in the presence of two subscrib-
ing witnesses.
